UNITED STATES PATENT OFFICE.

DAVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

Application filed August 12, 1921. Serial No. 491,727.

My invention relates to electric switches, more particularly of the oscillating snap switch type.

One object of my invention is to provide a simple strong snap action with a long break. Another object is to provide a switch of small dimensions which will carry heavy currents and therefore be especially useful in electric drill handles and other machines where such currents are used. Another object is to provide a handle which will prevent any blows it may receive from being transmitted to the switch mechanism.

In the drawings I have, for convenience, shown the mechanism installed in a tubular handle such as is found on electric drills and other electrical implements.

Fig. 1 is a plan view;

Fig. 2 is a broken section on line 2—2 of Fig. 1 showing the switch open;

Fig. 3 is another longitudinal section, showing the switch closed;

Fig. 4 is a cross section on the line 4—4 of Fig. 2;

Fig. 5 is a section on the line 5—5 of Fig. 2, showing the assembly of the stationary contacts and insulation;

Fig. 6 is a section on the line 6—6 of Fig. 2 showing the assembly of the terminals.

Figs. 7 and 8 are sectional views showing two styles of the shock resisting form of handle;

Fig. 9 is a perspective view of the moving contact and its spring and insulating link.

The frame of the mechanism consists of the insulating side pieces 1, which are spaced at the ends by the insulation strips 17 and 18. Screws 4 hold the frame together at the four corners and at both ends of the flanged metal top 3 which fits over the side pieces 1. Pivoted to this frame at 5 is the operating lever 6, which may have a handle or thumb piece 7 in one with the body of the lever, as shown in Figs. 1, 2 and 3. This lever can be

stamped out of one piece of metal and the thumb piece 7 formed by twisting that end at right angles to the body, but for some purposes it is desirable to form the projecting handle as hereinafter described in connection

with Figs. 6 and 7. In order to reduce the size of the switch as far as possible the body of the lever 6 is made of the angular form best seen in Fig. 3, to fit as far as possible around a moving contact member 8. Connecting the tip of the operating lever 6 and

the moving contact member 8, is a tension spring 10, and while I prefer to insulate the operating lever 6 at this point by an insulating link 11, the lever could instead, be insulated at other points.

The moving contact member 8 consists of two L-shaped contact blades, each having a short end notched to fit on one of pivot pins 14 set in the insulated sides 1. These contact blades are joined together at the elbow by a bridge 13 and the tension spring 10 is attached to this bridge, so that the moving contact member is thereby held against these pivot pins. These pins are set in the insulated sides 1 so that the insulation of the moving contact member 8 is thereby completed. The spring 10 is connected to the operating lever 6 at such a point that the pull on the bridge 13 of the moving contact member 8 swings from one side of the center of the pivots 14 to the other as the operating lever is moved. In this way I obtain oscillating snap action of the moving contact member. The free ends of the blades 12 act as contacts to engage corresponding stationary contacts 15 carried by the frame.

The assembly of the insulating strips of the frame and stationary contacts 15 and terminals 16 is shown best in Figs. 5 and 6. A central insulating strip 17 at each end of the frame acts as a stop for the operating lever 6. This can be seen in Figs 2 and 3.

At the end of the frame where the stationary contacts 15 are located this strip 17 also forms a barrier of insulation between those two contacts. On either side of the central insulating strip 17 lie two additional strips 18. Near the top of the switch these are long enough to act as stops for the bridge 13 of the moving contact 8 at the two extremes of its movements. Outside the strips 18 are the side pieces 1, the whole assembly being held together by the screws 4 as before described. The stationary contacts 15 and terminals 16 are mounted in these insulation strips. For each terminal and stationary contact there are terminal holding screws 9 passing through holes in each outer strip 18, which hold the contact blades 15 and terminal plate 16 of each terminal fast to their insulating strip and in electrical contact with each other. The inner strips 18 are recessed to accommodate the heads of these screws 9 as shown in Fig. 6 and the side pieces 1 have openings through them in which lie the

- terminal plates 16. In the drawings I have shown each stationary contact as having two blades, with one blade on each side of its outer strip 18. By letting the terminal holding screws extend a little distance outside the terminal plate they form retaining lugs for the wire which is fastened under a binding screw 19 located between them as shown in Fig. 6. By the described construction I obtain 10 brushing contacts having insulating material between the contacts on one side of the switch and the contacts on the other, as well as a long break. The carrying capacity of the switch is consequently much greater than 15 that of other switches of this size and style.
- As an additional means of insulation a fiber sheet 20 may be wrapped around the frame as shown in Fig. 4. The switch is inserted in the tubular handle 21 of any electrical 20 implement by sliding the handle into opening 22 in the tube and fastening the metal top 3 to the tube by screws 23.
- Switch handles are often accidentally hit and the switch mechanism damaged. This 25 is especially true in the case of electrical implements which are knocked and dropped frequently. Wherever it is desired to avoid the danger of such accidents the handle may be constructed to cushion the blow, as shown 30 in the modifications in Fig. 7 or that shown in Fig. 8. For this purpose, I may mount a spring-pressed ball 24 loosely on the handle shank 25, making the ball sufficiently large 35 to rest in the frame of the implement on both sides of the slot as well as the end. In this way the ball never lifts up clear of the slot in the casing of the implement and the effect of a blow struck on ball 24 never reaches the switch mechanism, being taken 40 up by the casing. Thus, while the handle shank 25 has an arcuate motion about the pivot 5 within the casing, the ball 24, or handle has a rectilinear motion above the casing outside of the slot.
- 45 In the type shown in Fig. 7 the ball 24 has a hole running through its center and a shank 25 of the operating lever 6 lies in this hole. A spring 26 on the shank 25 tends to

keep the ball pressed against the casing of the tool by being confined between the head 50 27 of the shank and the shoulder 28 at the lower end of the hole in the ball. In the type shown in Fig. 8 the hole does not extend through the ball. It will be apparent that this form of handle is adaptable to 55 other types of switch.

I claim:—

1. In a switch mechanism an insulated toggle contact member consisting of two L-shaped contact plates joined at their elbows 60 in combination with an insulating frame, a separate pivot pin on the frame for one end of each contact plate and an operating spring fastened to the joint between the plates.

2. In a switch mechanism, terminal plates, double bladed contacts insulated from each other and a binding screw connecting the blades of each contact and the corresponding terminal plate, in combination with a 70 central insulating strip having said contacts on opposite sides thereof and separating and isolating them from each other.

3. In a switch mechanism, a frame, a toggle contact member insulated from said frame, a tension spring to operate said toggle contact member and bladed stationary contacts cooperating with said toggle contact member, in combination with a one-piece combined operating member and handle shank controlling said spring and connected to said toggle contact member by said spring, and a link insulating said contact member from said combined member.

4. In a switch mechanism, a casing, and a handle shank projecting through a slot in the casing having an arcuate motion about a pivot within the casing, in combination with a handle loosely mounted upon said handle shank, and a spring on said shank 90 pressing the handle to the casing, said handle having a rectilinear motion along the casing outside of the slot.

In testimony whereof I have signed my name to this specification.

ARVID H. NERO.
